United States Patent Office

Des. 207,062
Patented Feb. 28, 1967

207,062

EATING TRAY

William K. Blair, Sr., 110 Mulberry St.,
Cambridge City, Ind. 47327

Filed Mar. 25, 1966, Ser. No. 1,629

Term of patent 14 years

(Cl. D44—10)

FIG-1

FIG-6

FIG. 1 is a perspective view of an eating tray showing my new design;

FIG. 2 is a top view thereof;

FIG. 3 is a side view thereof;

FIG. 4 is a bottom view thereof;

FIG. 5 is an other side view thereof; and

FIG. 6 is an end view thereof.

I claim:

The ornamental design for an eating tray, substantially as shown.
